UNITED STATES PATENT OFFICE.

RUEL S. BALDWIN, OF SPARTA, WISCONSIN.

MACHINE FOR FORMING WIRE SPRINGS.

SPECIFICATION forming part of Letters Patent No. 273,933, dated March 13, 1893.

Application filed July 10, 1882. (No model.)

To all whom it may concern:

Be it known that I, RUEL S. BALDWIN, of Sparta, in the county of Monroe and State of Wisconsin, have invented certain Improvements in Machines for Forming Wire Springs, of which the following is a specification.

The object of my invention is to produce a simple, efficient, and durable device for forming wire springs of exact uniformity as regards their size and length, and to form in the end coil of said spring a shoulder or bend to facilitate the firm attachment of the extremity of the wire thereto.

To this end the invention consists, first, in a rotary cone or former constructed with a groove wherein to wind the wire and with a movable cutter operating in connection with a stationary cutter or shoulder thereon to sever the wire when the spring is completed, the movable cutter being operated by a fixed pulley or equivalent bearing, against which it is carried by the rotation of the former.

It consists, second, in a bending-slide, also mounted upon the cone or former and operated in the same manner as the knife, the second slide having its end of such form as will act upon and bend or crook the wire at the required point.

Referring to the accompanying drawings, Figure 1 is a side elevation of my machine. Figs. 2 and 3 are sections of the same on the line *xx* and *yy*, respectively. Fig. 4 is a perspective view, showing the bending-slide detached. Fig. 5 is a plan view, showing the form of the spring as it is produced by the machine. Fig. 6 is a view showing the slide provided with both cutting and bending shoulders.

A represents the rotary driving shaft or arbor, which may be mounted in supports *L* of any suitable character and driven by means of a crank, pulley, or by gearing adapted to turn in the direction indicated by the arrow.

B represents the body of the former, upon which the wire is wound and by which the shape and size of the spring are determined. It may be of a conical form or of a cylindrical or any other form corresponding with that of the spring to be produced. The former is provided with a circumferential spiral groove, *a*, to receive the wire, and at its outer end is pref-

erably provided with a notch, *b*, or a pin, clip, or equivalent device to retain one end of the wire during the winding process. At its inner end, at or near the termination of the groove, the former *B* is provided with a fixed cutting shoulder or knife, *D*, coinciding with or forming one side of the groove at that point, so that the wire will be laid across and against it as the winding action is ended and the spring completed. The severance of the wire is effected by the co-operation of this fixed edge with a sliding blade, *E*, mounted in a longitudinal groove in the former *B*, moved endwise by being carried against the pulley *F*, or, its equivalent, an inclined bearing fixed in position on the frame. At each revolution of the former *B* the movable knife encounters and is pushed inward by the pulley, causing the cutting-edge *T* at its inner end to move past the shoulder *D*, thus severing the wire lying between the two. A spring, *K*, acting upon the sliding knife, moves the same outward as soon as it has moved past the pulley. The former is rotated in the direction indicated. The end of the wire being applied in the outer end of the groove, the wire is quickly wound into the latter from end to end. As the wire enters the inner end of the groove it passes between the two cutting-edges and is immediately severed thereby, thus releasing the finished spring.

In the formation of springs for use in mattresses and beds it is customary to attach the end of the wire to the wire itself at the beginning of the end coil. In order that the wire may be thus attached firmly and prevented from sliding at the point of connection, the wire is commonly bent or crooked at the point of attachment. To secure this bending of the wire, I apply to the cone or former a second slide, *I*, mounted and actuated in the same or substantially the same manner as the sliding cutter. The inner end of this second slide, however, instead of being provided with a cutting-edge, is made in the peculiar form represented in Fig. 4, with three projecting fingers, *d*, arranged in such manner that they will act upon the wire lying in the groove and give thereby the crook or bend desired. The essential feature of the invention as regards this

bending device consists in adapting the same to act upon the wire as stated, and it is obvious that the fingers may be dispensed with or modified in form, provided only that the 5 slide is adapted to give the required bend to the wire at the proper point.

Instead of using two separate slides, E and I, the cutting-shoulder and the bending fingers or shoulders may both be formed in one 10 and the same slide, the fingers at the inner end and the shoulder at the middle.

While it is preferred to employ the roller F to actuate the slide or slides because of the small amount of friction developed, it is obvious that a stationary inclined shoulder could 15 be substituted for the roller.

Having thus described my invention, what I claim is—

1. The rotary head or former provided with 20 the stationary cutting-shoulder and with the movable cutter, in combination with the fixed roller or its equivalent to actuate the movable cutter.

2. The rotary grooved head having the stationary shoulder or cutter, combined with the 25 sliding cutter seated therein, and the fixed pulley.

3. In a spring-forming machine, a rotary grooved head or former provided with the cutter, in combination with a movable cutter 30 mounted therein and carried therewith, and a stationary device, substantially as shown, to operate said movable cutter.

4. In a spring-bending machine, the combination of a rotary former whereon the wire 35 is wound and a movable bending-slide, substantially as described, to crook or bend the wire while wound upon the former.

5. In combination with the former, the slide provided with the three fingers and the stationary pulley arranged to actuate said slide. 40

6. In a machine for forming wire springs, the combination of a rotary head or former whereon the wire is wound, a cutting and bending slide located upon the former, and a stationary device, substantially as described, 45 to operate said slide.

RUEL S. BALDWIN.
